Primary Examiner — Michael A. Pratt(74) *Attorney, Agent, or Firm* — Ballard Spahr LLP(57) **CLAIM**

The ornamental design for a hand grip as shown and described.

DESCRIPTION

FIG. 1 is a right side isometric view, from above, of a hand grip according to the invention;

FIG. 2 is a right side view thereof;

FIG. 3 is a left side view thereof;

FIG. 4 is a front view thereof;

FIG. 5 is a rear view thereof;

FIG. 6 is a bottom view thereof; and,

FIG. 7 is a top view thereof.

The broken lines in the figures form no part of the claimed design.
